JOINT BREAKER

Harold L. Therolf, Los Nietos, Calif., assignor to
 Eason & Therolf Tool Company, Los Nietos,
 Calif., a co-partnership composed of Ernest L.
 Eason and Harold L. Therolf

Application June 30, 1936, Serial No. 88,123

7 Claims. (Cl. 254—173)

This invention relates to well drilling equipment and relates more particularly to an automatic cat head or joint breaker for use on or application to the draw works of a well drilling rig. 5 A general object of this invention is to provide a practical, effective automatic joint breaker that is safe and convenient to operate.

Another object of this invention is to provide an automatic joint breaker intended for application to the line shaft of a draw works that may be governed or engaged from a remote point to exert a pull on tongs or the like for breaking a joint in a drilling string, or the like, at the rotary table.

15 Another object of this invention is to provide an automatic joint breaker that exerts or applies a pull of limited and known extent and then releases, whereby it is particularly safe to use or operate.

20 Another object of this invention is to provide an automatic joint breaker of the character mentioned in which the moving or working parts are entirely enclosed and cannot foul the lines or injure the workmen.

25 Another object of this invention is to provide an automatic joint breaker of the character mentioned that embodies a simple, dependable clutch and a clutch control operable from a convenient remote point to engage the tong-line drum with 30 the line shaft of the draw works.

Another object of this invention is to provide an automatic joint breaker of the character mentioned embodying a novel effective means for automatically disengaging or de-clutching the 35 tong-line drum when the drum has been turned substantially one revolution thereby rendering the device safe to operate under practically any conditions.

Another and important object of the invention 40 is to provide an automatic joint breaker of the character mentioned that may be easily and quickly assembled in the line shaft even though the shaft wobbles or is out of alignment.

A further object of this invention is to provide 45 an automatic joint breaker of the character mentioned that is simple and inexpensive and that is adapted to be applied to the line shafts of the various typical makes and forms of draw works.

The various objects and features of my invention 50 will be fully understood from the following detailed description of a typical preferred form and application of my invention, throughout which description reference is made to the accompanying drawing, in which:

55 Fig. 1 is a fragmentary elevation view of a por-

tion of a typical draw works illustrating the joint breaker of the present invention in its operative position. Fig. 2 is an enlarged vertical detailed sectional view of the joint breaker being a view taken as indicated by line 2—2 on Fig. 1. Fig. 3 5 is a longitudinal detailed sectional view of the joint breaker taken as indicated by line 3—3 on Fig. 2. Fig. 4 is a fragmentary transverse detailed sectional view taken substantially as indicated by line 4—4 on Fig. 3 and illustrating the clutch 10 means and Fig. 5 is a fragmentary horizontal detailed sectional view taken substantially as indicated by line 5—5 on Fig. 4.

The improved joint breaker of the present invention is adapted to be employed in connection 15 with draw works of various makes and types. In the drawing I have illustrated a portion of a typical draw works as used in well drilling operations and have shown a typical preferred embodiment of the invention operatively applied to 20 the draw works. It is to be understood that the invention is not to be construed as limited or restricted to the specific form or application about to be described, but is to be taken as including any features or modifications that may fall within the 25 scope of the claims.

The portion of the typical draw works illustrated includes a frame having a header 10 and a post 11. A substantially horizontal line shaft 12 is rotatably supported by bearings (not shown) 30 and has an end portion extending laterally from one side of the post 11. A drum shaft 13 is spaced below the line shaft 12 and is rotatably carried by a bearing 14 on the post 11 and a similar bearing on the other post (not shown) of the 35 frame. The drum shaft 13 carries the usual winding drum 15. The portion of the drum 15 illustrated has a brake flange 16 engageable by the usual lined brake band 17 for controlling the rotation of the winding drum. A chain and 40 sprocket drive 18 is provided between the line shaft 12 and the drum shaft 13. It is to be understood that the line shaft 12 is driven or operated by the drilling engine of the rig.

The automatic joint breaker of the present invention includes, generally, a case or housing 20 surrounding the end portion of the line shaft 12, a sleeve or collar 21 secured to the shaft 12 within the housing 20, a cat head or spool 22 on the collar 21, a shiftable tong-line drum 23 in the 50 housing 20, clutch means 24 adapted to form a drive between the collar 21 and the drum 23, means 25 for shifting the drum 23 to engage the clutch means 24 and means 26 for automatically returning the drum 23 to disengage the clutch 55

means 24 at the termination of substantially one revolution of the drum 23

The case or housing 20 is provided to enclose the moving or working parts of the device to prevent the fouling of lines, etc. with the device, and to protect the workmen against injury. The housing 20 is relatively stationary and is rotatably mounted on the projecting portion of the shaft 12 in the manner to be hereinafter described. In the typical form of the invention illustrated the housing 20 is a substantially cylindrical hollow structure comprising two complementary sections 20^a connected by axially extending flange and bolt connections 27. The housing 20 is provided with normal inner and outer ends 28 and 29. A radial inwardly facing annular flange 30 is provided on the interior of the inner end 28. An outwardly projecting wall section extends from the outer end 29 of the housing 20 and has an angular lip or flange 32 at its outer end. Means is provided for preventing rotation of the housing 20. A stop lug 33 projects from the upper section 20^a and is adapted to abut or bear against a convenient or suitable abutment to hold the housing against turning in one direction. In the particular application of the invention illustrated in the drawing the post 11 forms the abutment for the lug 33; that is, the lug 33 abuts against the stationary abutment or post 11 to prevent rotation of the housing 20 with the shaft 12. A bolt 90 passes through an opening 91 in the lug 33 with substantial clearance. The bolt 90 has a shoulder 92 engaging against the post 11 to prevent the head of the bolt from clamping the lug against the post. A reduced portion of the bolt 90 passes through an opening in the post 11, or a flange of the post 11, and has a threaded nut 93 to hold the bolt in place. The lug 33 is only loosely engaged on the bolt 90 and does not serve to secure the housing 20 to the post but merely holds the housing against rotation in both directions. The loose association of the housing 20 with the abutment or post 11 is important as it allows the joint breaker to be easily and quickly arranged on the shaft 12 even though the shaft is out of alignment. It is apparent that the lug 33 or another part of the housing 20 may engage any suitable stationary abutment to hold the housing against rotation with the shaft 12. The housing 20 just described surrounds the end portion of the line shaft 12 with substantial clearance to receive the collar 21, the drum 23 and the associated parts.

The collar 21 is provided to shiftably support the line drum 23 and to present certain clutch parts of the means 24 to be hereinafter described. The collar 21 is a tubular member of substantial length surrounding the shaft 12 at one side of the post 11 and extending through the housing 20. In practice the collar 21 may project outwardly beyond the end of the shaft 12 as illustrated in the drawing. A feather or key 34 cooperates with suitable key-ways 35 in the shaft 12 and the collar 21 to connect the collar with the shaft for rotation therewith. The major portion of the collar 21 is cylindrical and of uniform diameter. The inner end portion of the collar 21 is preferably of enlarged diameter and is provided with an annular groove 36. The housing 20 surrounds a portion of the rotatable shaft 12 and is held against rotation with the shaft by the engagement of its lug 33 with the abutment or post 11 so that it is desirable or necessary to provide bearing means for supporting the non-rotatable housing on the rotatable

shaft. A bushing or bearing 37 is arranged in the groove 36 and receives the flange 30 of the housing 20. The housing 20 is thus rotatably supported on the shaft 12 through the medium of the flange 30, bearing 37 and collar 21. Suitable lubricant ports 38 are provided in the bearing 37. A lubricant reservoir 39 may be provided on the upper portion of the housing 20 and a port 40 may extend downwardly through the housing 20 from the reservoir 39 to the flange 30 to conduct lubricant to the bearing 37. An annular flange 41 is provided on the collar 21 at the outer side of the groove 36 to carry certain clutch parts of the means 24 as will be hereinafter described.

The cat head or spool 22 is provided to replace the cat head usually provided on the end of the line shaft 12 and has the same uses as the usual cat head. The spool 22 is secured to the projecting end portion of the collar 21 to rotate with the shaft 12. The spool 22 is cylindrical in its general configuration and has annular flanges 42 at its opposite ends to prevent the displacement of the line. The spool 22 is preferably made hollow to lighten its weight and reduce its cost. In practice the spool 22 may be tubular and its outer end may be closed by a plate 43 secured in place by a spring ring 44. The cat head or spool 22 is threaded on the projecting end portion of the collar 21 and is locked against unthreading by a feather or key 45. The inner flange 42 of the spool 22 is received in the angular flange 32 of the housing 20 and the inner end of the spool acts to close the outer end of the housing.

The drum 23 is provided to pull or operate a line L which in turn may pull or operate tongs or other tools in the rig. The drum 23 is arranged in the housing 20 and is shiftable axially therein. In accordance with the invention the drum 23 is a tubular member surrounding the major cylindrical portion of the collar 21. The drum 23 is preferably rotatably and shiftably supported on the collar 21 through a suitable bearing or bushing 46. The bushing 46 may be shiftable with the drum 23. An annular internal groove 47 is provided in the drum 23 to carry lubricant for the bushing 46. A port 48 extends outwardly through the drum 23 to conduct lubricant to the groove 47. An annular external channel or groove 49 is provided in the drum 23 to receive or wind in the line L. An opening 98 is provided in the wall of the housing 20 to facilitate the lubrication of the bushing 46 and is normally closed by a door 99.

An end of the line L is secured to the drum 23. In accordance with the invention any suitable means may be provided for securing the line L to the drum 23. In the particular structure illustrated a tubular rope socket 50 is fixed in the groove 49 to receive the line L. The inner end part 51 of the line L is spread or enlarged to prevent the line from being pulled outwardly through the socket 50. The line L extends from the joint breaker and is adapted to be connected with a tool, for example, tongs, for breaking the joints of a string extending through the rotary. An opening 52 is provided in the lower wall portion of the housing 20 in alignment with the groove 49 to pass the line L. The opening 52 is horizontally elongated. A tangential tubular guide 53 may be provided on the body 20 at the opening 50 to guide the line L.

The clutch means 24 is operable to impart rotation from the collar 21 to the drum 23 for the purpose of winding the line L on the drum and thus effect pulling of the line L and operating

of the tool connected therewith. The clutch means 24 includes a plurality of circumferentially spaced clutch parts 54 on the inner end of the drum 23. The clutch parts 54 have flat radial faces 55 opposing the direction of rotation of the shaft 12 and inclined surfaces 56 sloping away from the tops or extremities of the surfaces 55. The means 24 further includes clutch parts on the flange 41 of the collar 21. The clutch parts on the flange 41 comprise flat radial faces 57 facing in the direction of rotation of the shaft 12 and inclined surfaces 58 sloping away from the tops of the faces 57. The faces 57 and the surfaces 58 may constitute walls of spaced notches in the outer side of the flange 41. These notches are adapted to receive the clutch parts 54 with suitable clearance. Upon inward shifting of the drum 23 the inclined surfaces 56 and 58 are adapted to cooperate to provide for smooth meshing or engagement of the clutch parts. The faces 57 are adapted to cooperate with the faces 55 to transmit rotation from the collar 21 to the drum 23.

The means 25 is adapted to be operated from any suitable remote point to effect axial shifting of the drum 23 to engage the clutch means 24 described above. The means 25 includes a lever or bell crank pivoted on a pin 60 supported by spaced lugs 61 on the upper side of the housing 20. The bell crank has an arm 62 projecting downwardly or inwardly through an opening 63 in the wall of the housing 20 and an outwardly and axially projecting arm 63. An annular groove 64 is provided in the outer end portion of the drum 23 and a cup-like member 65 seats in the upper portion of the groove 64. The member 65 also bears on the cylindrical periphery of the drum 23. The inner end of the arm 62 is rounded to cooperate with or seat in the member 65.

The means 25 may further include a line 66 connected with the outer bell crank arm 63. The line 66 extends from the arm 63 and may pass over suitable pulleys 67 on the header 10 to a convenient point for actuation. Pulling of the line 66 effects inward swinging of the arm 63 which in turn shifts the member 65 and the drum 23 inwardly to engage the clutch means 24. Spring means may be associated with the means 25 to yieldingly hold the drum 23 in its de-clutched position. In the particular case illustrated in the drawing an extensible coiled spring 68 is connected with the arm 63 and a lug 61 to urge the arm 63 to the position where the drum 23 is idle.

The means 26 for automatically de-clutching the drum 23 from the collar 21 and the shaft 12 is an important feature of the invention as it renders the device entirely safe to operate. The means 26 is a simple cam means that automatically shifts the drum 23 axially outward at the termination of substantially one complete rotation of the drum. The automatic de-clutching means 26 includes a lug 70 projecting inwardly from the upper wall portion of the housing 20 and a cam 71 on the inner end of the drum 23. The projection 70 may have substantially flat parallel sides as illustrated in the drawing. The cam 71 has a flat end surface 72 facing counter to the direction of rotation of the shaft 12 and an inclined or pitched surface 73 on its forward side. The cam face 73 is of substantial length and is adapted to cooperate with the lug 70 to shift the drum 23 axially or outwardly a sufficient distance 75 to disengage the clutch parts 54 from the clutch

parts of the flange 41. A flat axial face 100 is provided at the outer end of the cam face 73. The projection or lug 70 and the cam 71 are related so that when the flat face 72 of the cam is in cooperation with the lug 70 the rope socket 5 is adjacent to and in alignment with the opening 52 as illustrated in Fig. 2.

It is believed that the operation of the automatic joint breaker of the invention will be apparent from the foregoing detailed description. The line L is adapted to be connected with tongs or any other similar tool in the drilling rig. The shaft 12 may be constantly rotating and the spring 68 holds the drum 23 in its retracted position where the clutch parts 54 are out of engagement with the clutch parts on the flange 41. When the drum 23 is in this normal position the flat face 72 of the cam 71 is in engagement with the lug 70. When it is desired to operate the tongs or tool connected with the line L the operator pulls the line 66 to shift the drum 23 inwardly. As the drum 23 shifts inwardly the inclined surfaces 56 and 58 may come into engagement to facilitate the smooth engagement of the flat clutch faces 55 with the faces 57. When the faces 55 and 57 are in cooperation the drum 23 of course rotates with the collar 21 and the shaft 12. As the drum 23 rotates the line L is wound or wrapped into the groove 49 and is thus actuated or pulled to operate its tongs. The rotation or turning of the drum 23 continues until the cam 71 cooperates with the lug 70. The cam face 73 cooperates with the lug 70 to shift the drum 23 axially or outwardly. As above described the surface 73 is formed to shift the drum 23 outwardly to fully disengage the clutch parts 54 from the clutch parts on the flange 41. This, of course, completely de-clutches the drum 23 from the collar 21 and the shaft 12. The face 100 definitely limits the movement of the drum 23. Thus the joint breaker is operable to exert a limited or definite pull on the line L and no more, so that there is no danger in the operation of the tongs or tool. To recondition the device for a succeeding operation the line L is pulled outwardly to effect reverse rotation of the drum 23. The flat face 72 of the cam 71 is adapted to strike the lug 70 to limit this reverse rotation of the drum 23 and set the drum in position for a second operation. The spring 68 acts to yieldingly hold the drum 23 in its de-clutched position and to automatically return the line 66.

The automatic joint breaker of the present invention is entirely safe to operate and is adapted to give tongs or similar tools a definite and known pull or stroke of movement. The operating parts of the device are entirely enclosed against dirt and so that they cannot foul the lines or injure the workmen. The joint breaker is such that it may be easily and quickly assembled on the line shaft of a typical draw works with little or no alteration of the draw works structure. The device is simple and easy to operate and is inexpensive to manufacture.

Having described only a typical preferred form and application of my invention, I do not wish to be limited or restricted to the specific details herein set forth, but wish to reserve to myself any variations or modifications that may appear to those skilled in the art or fall within the scope of the following claims.

Having described my invention, I claim:

1. A joint breaker for application to the shaft of a draw works having a post, said joint breaker including, a housing surrounding the shaft, a

- member arranged on the shaft to rotate therewith and extending into the housing, means rotatably supporting the housing on the member, a rotatable and axially shiftable drum arranged on the member, a tool operating line associated with the drum to be wound thereon, clutch means engageable by axial shifting of the drum in one direction to cause the drum to rotate with the shaft, means for shifting the drum in said direction to engage the clutch means, cam parts on the drum and housing cooperable to shift the drum in the opposite direction to disengage the clutch means when a predetermined length of the line is wound on the drum, and means loosely associating the housing with the post to prevent rotation of the housing.
2. A joint breaker for application to the shaft of a draw works including, a housing surrounding the shaft, a member in the housing arranged on the shaft to rotate therewith, a bearing rotatably supporting the housing on the member, a rotatable and axially shiftable drum arranged around the member, a tool operating line associated with the drum to be wound thereon, clutch means engageable by axial shifting of the drum in one direction to cause the drum to rotate with the shaft, means for shifting the drum in said direction to engage the clutch means, cam parts on the drum and housing cooperable to shift the drum in the opposite direction to disengage the clutch means when a predetermined length of the line is wound on the drum, and means loosely associating the housing with a relatively fixed abutment to prevent rotation of the housing.
3. A cat head for use in combination with a rotatable shaft and a relatively stationary abutment, the cathead including a collar secured to the shaft to rotate therewith, a rotatable line drum shiftable axially with respect to the shaft, clutch parts on the collar and drum cooperable upon shifting of the drum in one direction to effect rotation of the drum, means for shifting the drum in said direction to effect engagement of the clutch parts, a housing surrounding the drum, bearing means supporting the housing on the collar, cooperable parts on the drum and housing for shifting the drum in the other direction to effect disengagement of the clutch parts, and a stop part on the housing engaging against the abutment to prevent turning of the housing and shiftable relative to the abutment to allow lateral working of the housing with the shaft.
4. A cat head for use in combination with a rotatable shaft and a relatively stationary abutment, the cathead including a collar secured to the shaft to rotate therewith, a rotatable line drum shiftable axially with respect to the shaft, clutch parts on the collar and drum cooperable upon shifting of the drum in one direction to effect rotation of the drum, means for shifting the drum in said direction to effect engagement

of the clutch parts, a housing surrounding the drum, bearing means spaced axially of the shaft for supporting the housing on the collar, cooperable parts on the drum and housing for shifting the drum in the other direction to effect disengagement of the clutch parts, and a stop part on the housing engaging with the abutment to prevent turning of the housing and shiftable relative to the abutment to allow lateral working of the housing with the shaft.

5. In combination with a rotatable shaft and a stationary abutment, two elements, one a member rotatable with the shaft, the other a rotatable drum, one of said elements being shiftable axially of the shaft relative to the other, clutch parts on the elements cooperable to effect rotation of the drum with the shaft upon axial shifting of said shiftable element in one direction, a housing for said elements, means rotatably supporting the housing on the member, means loosely associating the housing with said abutment to prevent turning of the housing and to allow lateral working of the housing, means for shifting said shiftable element in the direction to engage the clutch parts, and cooperable cam parts on the housing and said axially shiftable element to shift said shiftable element in the other direction to effect disengagement of the clutch parts.

6. A cat head for use in combination with a rotatable shaft and a relatively stationary abutment, the cat head including a collar secured to the shaft to rotate therewith, a rotatable line drum shiftable axially with respect to the shaft, clutch parts on the collar and drum cooperable to effect rotation of the drum, a housing for the drum rotatably supported on the collar, means for shifting the drum to engage the clutch parts, cooperable parts on the housing and drum for shifting the drum to disengage the clutch parts, a projection on the abutment, and a part on the housing engaging against the abutment and having an opening loosely receiving said projection to prevent rotation of the housing and to allow lateral working of the housing with the shaft.

7. A cat head for use with a shaft and a post, the cat head including an assembly comprising a collar adapted to be slid over the shaft, a drum carried by the collar to rotate and shift axially thereon, a housing, and bearing means rotatably supporting the housing on the collar to surround the drum, means for securing the collar to the shaft to rotate therewith, cooperable clutch parts on the collar and drum to effect rotation of the drum, means for shifting the drum to engage the clutch parts, cooperable parts on the drum and housing for shifting the drum to release the clutch parts, and a stop on the housing engaging with the post to prevent rotation of the shaft and shiftable with respect to the post to allow lateral working of the housing.
